GARMENT SHIELD

Mathew Saari and Victor De Cesare, Baltimore,
Md., assignors to J. Schoeneman, Incorporated,
Baltimore, Md., a corporation of Maryland

Application January 16, 1948, Serial No. 2,707

6 Claims. (Cl. 2—53)

1

This invention relates to a garment shield primarily adapted to be sewed into a coat or jacket under the arm to prevent wear or wrinkling of that part of the garment and to prevent perspiration from injuring the garment. The invention is primarily directed to a one piece shield which may be completely finished with only one line of stitching. It may be made in any desired size and after sewing in the armpit, it requires tacking at only one point to be maintained in smooth position. It may of course be made of the same material as the garment lining and it presents a smooth outer surface of one piece and from its outward appearance, it appears to be only one piece of cloth with the edges turned in or under, and in fact these edges are not only turned in but are stitched together at the center of the back to complete the one piece shield. It will of course be apparent that the shield may be placed adjacent to other openings in garments where it may be desired to protect the garments, as well as adjacent the attachment of the sleeve to the coat or jacket.

Other advantages and objects of the invention will be apparent from the following description and the accompanying drawings forming a part hereof and in which:

Figure 1 shows the inside of a coat with the shield attached at the lower side of the armhole.

Figure 2 is an enlarged cross sectional view on line 2—2 of Figure 1.

Figure 3 is a rear elevation of the shield.

Figure 4 is an elevation of the shield extended, showing the fold lines.

Figure 5 is an elevation showing the shield of Figure 4 folded double, after stitching.

Figure 6 is an end view from the top of Figure 5.

Figure 7 is a rear elevational view of the shield of Figure 5 turned right side out and pulled into its triangular shape.

Figure 8 is a sectional view on line 8—8 of Figure 7, before the back of the shield has been pressed into place.

In the drawings similar numerals refer to similar parts throughout the several views:

The shield 1 may be stitched into the arm pit of the coat as shown in Figures 1 and 2 in which the body of the coat 2 has had the sleeve 3 and its padding 4 with the lining for the coat 5 and for the padding 6 stitched therein. The shield is then placed under the lining 7 for the sleeve and that lining and the shield are then stitched to the coat body lining 5 as shown at 8.

2

The shield is initially made from a substantially rectangular piece of cloth having an exact shape or pattern as shown in Figure 4. The top 9 is concave, to fit the coat armhole, the ends 10 are similarly concave, each to coincide when folded with one half of the top 9. The bottom 12 is generally convex and notched at 13, the tip of the triangle. The rectangle is cut with its general directions being with those of the warp and woof of the cloth. After cutting out the pattern in this shape, the rectangle, having a length of substantially twice its depth, is doubled upon itself inside out, into a square as shown in Figure 5 and then stitched together along its lower edge as shown at 14. The sack thus formed is then turned right side out and grasped on both sides at the substantial center 15 of the squares as shown in Figure 5, between the forefinger and thumb of each hand, and pulled. This action tends to stretch the formerly substantially square sack into the form roughly of a triangle or wedge, as shown in Figure 7. This configuration may be more closely described as having the shape of an inverted gambrel roof. When the two sides are pulled out as far as possible it will be apparent that the direction of the threads in the cloth at the front extend in the direction of pull and the back is extended, being folded on a bias until it bulges outwardly as shown at 16 in Figure 8. This bulge or fullness is then pressed down into the diamond formation as shown at 17 in Figure 3 and in anticipation at 17 in Figure 7 and since this formation is at the rear or back of the shield it not only is not apparent but forms additional layers of thickness for wear and for the stiffening of the shield to hold the shield in proper place and extended crosswise across the armpit of the coat.

After sewing the shield in at the top under the lining of the sleeve, as above described, it need only be tacked at the point 13 to the garment for it to be permanently attached so that it does not thereafter wrinkle or lose its smooth appearance in wear. It will be apparent that the diamond shaped fold not only takes up the bulge or fullness in the back of the shield but that it forms this additional reinforcement of the shield to hold it outwardly extended so that the corners 15 are held in their extended position. These corners 15 having formerly been the centers 15 of the cloth after its first fold.

It will be apparent that a one-piece shield with its only seam being concealed and in which the shield is reinforced for it to hold its own

55

shape, by its own body structure, is thus presented having its only raw edges at the top which are concealed upon sewing the shield into place under the coat arm and covering it with the sleeve lining.

It will also be apparent that the size of the shield is determined solely by the size of the initially cut piece of cloth and that it may be made of the same material as the lining of the coat and thus be quite inconspicuous. Other changes may be made to the shield without departing from the invention as covered by the following claims.

What is claimed as new and is desired to be secured by Letters Patent is:

1. A wedge shaped garment shield of one piece of cloth and of double thickness having as its only seam a vertically directed seam in the center of the back, the seamless shield edges each having therein an outwardly directed obtuse angle to give greater width to the shield midway its depth, the cut and fold of the shield producing a fullness in the seamed side of the shield, and a fold portion in the seamed side of the shield to take up the fullness therein.

2. A one piece garment shield having a face shaped like the cross section of an inverted gambrel roof, and having seamless edges, the back being formed of overfolded sections from the front and joined by a single central vertical seam, stitched before the shield was turned right side out, to conceal the stitches, the top of the front and back coinciding and being adapted to be attached to a garment opening, the cut and fold of the shield producing a fullness in the seamed side of the shield, and a fold portion in the seamed side of the shield to take up the fullness therein.

3. A one piece garment shield having a face shaped like the cross section of an inverted gambrel roof, and having seamless edges, the back being formed of overfolded sections from the front and joined by a single central vertical seam, stitched before the shield was turned right side out, to conceal the stitches, the top of the front and back coinciding and being adapted to be attached to a garment opening, the formation of the angled seamless edges of the shield due to the original shape of the pattern, causing a fullness at the back, and that fullness being pressed flat, in diamond formation across the width of the back of the shield intermediate its depth, the angles of the edges being adjacent opposite diamond points.

4. The method of making a garment shield comprising doubling in the outside of a roughly rectangular piece of cloth which is substantially twice as long as wide into a square and stitching one edge, leading from the fold, turning the piece right side out, flattening it into substan-

tially triangular form, with the seam in the vertical center of the triangle of one side, forming the back, and the other side presenting a smooth shield surface, and the overfolded ends of the piece coinciding with the top of the triangle, those ends and top presenting the only raw edges and being adapted to be stitched into a garment opening.

5. The method of making a garment shield comprising doubling, in the outside of a roughly rectangular piece of cloth, which is substantially twice as long as wide, one long edge being concave, the other convex, into a square and stitching the convex edge, leading from the fold, turning the piece right side out, flattening it into wedge form with the concave edge being at the wedge top and the ends of the piece coinciding therewith, with the seam in the vertical center of the wedge on one side, stretching the mid-points of the wedge sides to form the seamed side of the shield into a diamond shaped fold and pressing the same flat, whereby the diamond shaped fold reinforces the angled edges of the wedge, to hold them extended.

6. A garment shield formed from a single piece of cloth of initially roughly rectangular shape which is substantially twice as long as wide and having four corners and a single line of stitching, the formed shield first having one long edge of the rectangle folded double upon itself so that the corners at one end of the rectangle overlie those at the other end and the said long edge being stitched from the fold to the overlying corners in the extremities of said long edge and the piece then being turned to place the seam inside, then having the two stitched corners on the stitched edge folded to the center of the opposite long edge into roughly a triangular form having two closed seamless edges, the ends of the rectangle coinciding with the said opposite long edge, the double top being the only exposed raw edge and it being adapted for attachment to a garment opening the closed seamless edges extending to the double top.
